INVENTOR

BY Victor J. Evans

ATTORNEY

UNITED STATES PATENT OFFICE

JOHN P. SCOTT, OF PITTSBURGH, PENNSYLVANIA

FLAG HOLDER

Application filed January 31, 1930. Serial No. 424,972.

This invention relates to flag staffs and holders therefor, an object being to provide a staff having novel means for removably securing a flag thereto, together with a holder for the staff and novel means for retaining the holder, staff and flag assembled.

Another object of the invention is the provision of a holder which is especially adapted for attachment to the bumpers of an automobile.

10 Another object of the invention is the provision of a combined flag staff and holder which is simple in construction, attractive in appearance and may be manufactured and sold at a nominal cost.

15 With the above and other objects in view, the invention further includes the following novel features and details of construction, to be hereinafter more fully described, illustrated in the accompanying drawings and 20 pointed out in the appended claim.

In the drawings:—

Figure 1 is a front elevation of the invention applied to the bumper bars of an automobile.

25 Figure 2 is a rear view of the same.

Figure 3 is a side view with the bumper bars and holder in section.

Figure 4 is a detail perspective view of 30 the clamping plate.

Figure 5 is a fragmentary section on the line 5—5 of Figure 2.

Figure 6 is a section on the line 6—6 of Figure 5.

35 Figure 7 is a section on the line 7—7 of Figure 5.

Figure 8 is a fragmentary elevation showing a portion of the flag and the flag engaging bar.

40 Figures 9 and 10 are fragmentary sectional views illustrating modified holders for the staff.

45 Referring to the drawings in detail wherein like characters of reference denote corresponding parts, the reference character 10 indicates a flag staff which is of tubular construction and preferably made of metal. This staff is open at opposite ends and is provided with a longitudinal slot 11 which extends inwardly from one end.

The reference character 12 indicates a bar which is preferably made of relatively thin sheet metal, bent upon itself to provide spaced walls 13 for the reception of the inner end of a flag or pennant 14. The walls 13 are forced inwardly or crimped at spaced intervals as indicated at 15 so as to provide a positive engagement with the flag. The remaining portions of the bar 12 are of a double thickness so as to stiffen and strengthen the bar.

55 One end of the bar is positioned within a kerf 16 provided in a carrier block 17 and is retained therein by means of a screw 18 which passes through an opening 19 provided in one end of the bar. The opposite end of the bar is received within a kerf 20 provided in the inner end of a ball or other ornament 21 whose reduced end 22 fits within the end of the tubular flag staff. A screw 23 removably secures the bar to the ball. The ball is clamped upon the flag or pennant and the latter is inserted within the slot 11, the carrier block 17 being inserted within the tubular staff and positioned at the lower end thereof 60 with the ball closing the upper end.

65 The staff is then inserted within a socket 24 provided in a holder 25 and a screw 26 which passes through one wall of the holder and through the tubular staff 10 into the block 17 serves to hold these parts assembled.

70 The holder is especially adapted for attachment to the bumper bars 27 of an automobile and for this purpose the holder is provided with an opening 28 and a notch 29. The holder is positioned against the inner faces of the bars 27 and a clamping plate 30 is positioned against the outer faces of these bars. This plate is provided with a positioning lug 31 which passes between the bars 27 and rests upon the upper edge of the lower bar. A bolt 37 passes through the plate between the bars, and through the opening 28 of the holder and is engaged by a nut 38 to secure the holder to the bumper bars.

75 It will be apparent that a soiled or torn flag may be readily replaced when desired, or if desired a flag mounted upon a wooden staff may be inserted within the tubular staff.

80 It is of course obvious that the invention 85

100

may be used with holders different from that previously described. For example, in Figure 9 there is provided a holder or base 39 having a socket 40 therein to receive the end of the flag staff. A screw 41 serves to removably hold the staff within the holder. This form of holder may be used for show windows, school rooms, speaker's tables, etc., being capable of resting upon any flat surface.

10 In Figure 10 a base 42 is shown. This base is provided with a socket 43 for the reception of the flag staff and the latter is held in place by a screw 44. A downwardly extending 15 penetrating member 45 projects from the underface of the base and is adapted to be inserted within the ground so that the staff may be supported upon lawns and any other places into which the member 45 may be forced.

20 The invention is susceptible of various changes in its form, proportions and minor details of construction and the right is herein reserved to make such changes as properly fall within the scope of the appended claim.

25 Having described the invention what is claimed is:—

30 In a flag staff, a tubular member having a longitudinally disposed slot therein for the passage of a flag, an elongated clamping member disposed longitudinally within the tubular member to engage the inner end of the flag, means secured to opposite ends of the clamping member and engageable within the 35 tubular member to hold said clamping member rigid with respect to said tubular member, a holder, and combined means to secure the tubular member within the holder and prevent removal of the clamping member.

40 In testimony whereof I affix my signature.
JOHN P. SCOTT.
